AUTOMATIC VALVE

Filed Aug. 20, 1926

UNITED STATES PATENT OFFICE

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA

AUTOMATIC VALVE

Application filed August 20, 1926. Serial No. 130,423.

This invention relates to an automatic valve which is closed by an added weight of liquid running into a counterbalanced receptacle and opened by the counterbalance upon 5 evaporation of such added liquid weight from the receptacle.

More specifically this invention has reference to an automatic control valve useful in circulatory refrigerating systems wherein 10 all of the liquid refrigerant flows through the valve, is evaporated for purposes of refrigeration, and thence flows back to means whereby it is re-liquified.

An object of this invention is to provide a 15 novel control for valves of this character which is intermittently actuated to effect closure of the valve by added weight diverted from the normal flow, and is automatically re-opened incident to evaporation of such 20 added weight.

Other objects and advantages will be apparent from the following description of a typical embodiment of my invention, while the subjoined claims serve to define those 25 features deemed novel in the art.

In the drawings:

Fig. I is a view partly in section and partly in elevation illustrative of my improved automatic valve; and,

Fig. II is a sectional view taken as indicated by the arrowed lines II-II in Fig. I.

Referring more in detail to the drawings my automatic valve is enclosed in a cylindrical casing or—what is commonly termed a 30 “boiler” 1—having one end 2 permanently closed-in and the other fitted with a removable head 3 secured thereto in any convenient manner. The removable head 3—as well as the shell flange 4 to which it is attached—is 35 of heavy section, whereas the boiler body 1 is relatively thin; and said head is provided with an open-top compartment 5 of substantial proportions to house the valve control 40 free of external liquid influence. This compartment 5 conveniently—though not essentially—conforms to the bore of the boiler shell 1 with its major depth well above half the diameter thereof, while its end wall 6 is provided with a bearing boss 7. The bearing 45 boss 7 is bored to snugly receive a hollow

shaft 8 as well as to accommodate packing 9 held in place by means of a screw gland 10 whereby leakage around the shaft 8—from the boiler 1 into the compartment 5—is prevented. 55

Liquid refrigerant is supplied to the boiler 1 by way of a conduit 11 having a discharge 12 under control of the closure device 13 carried by one arm 14 of an angled member 15 clamped on the tubular shaft 8 by a set screw 16, whereas the other arm 17 of said angled member affords support for an adjustable counterweight 18.

The proper inflow control of refrigerating medium into the casing 1 is accomplished by 65 a tubular receptacle 19 provided with a screw-threaded boss 20 by means of which it is attached to that end of the hollow shaft 8 projected into the open-top compartment 5. The tubular receptacle 19 has its lower end 70 closed in by a relatively-heavy cap-piece 21, while it is locked at the required adjustment on the shaft 8 by a set screw 22. It will be seen that, as liquid rises in the boiler 1 to the level of the shaft 8 it will flow therethrough 75 into the tubular receptacle 19. A collar 23 provided with a clamping screw 24 serves to prevent lateral movement of the shaft 8; while the counterweight 18 is adjusted on the arm 17 at such position that it slightly overbalances the cap-piece 21 of the receptacle 19 when empty. A laterally directed stop 25 is provided in the open-top compartment 5 to prevent the receptacle 19 assuming a horizontal position under the action of the counterweight 18. 80

The operation of my novel automatic valve is as follows: Assuming the receptacle 19 is empty, the counterweight 18 holds the closure device 13 away from the discharge 12, 90 which jointly constitute the control valve in a circulatory refrigerating system. As a result, refrigerating medium in liquid form enters through the discharge 12 into the boiler 1 and rises till it overflows by way of the hollow shaft 8 into the receptacle 19 until the latter overbalances the counterweight 18. The added weight of liquid refrigerating medium in the receptacle 19 causes the same 95 to rotate and swing the device 13 into clo- 100

sure position over the discharge 12, thereby arresting further inflow of liquid into the boiler 1. As the added weight of liquid in the receptacle 19 evaporates, the said receptacle will rotate in an opposite direction until the cap-piece 21 engages the lateral stop 25; and, simultaneously, the closure device 13 will have been removed from over the discharge 12. Particular attention is drawn to the fact that as the liquid in the receptacle 19 evaporates, the level of the liquid in the boiler 1 is similarly lowered by evaporation. Upon re-opening of the discharge 12 the liquid level in the boiler 1 again rises until it reaches the bore of the hollow shaft 8, whereupon the cycle of operations above set forth are automatically repeated.

The receptacle 19 operates in the open-top compartment 5 free of all external liquid interference and it is alternately rocked by the added weight of liquid refrigerant overflowing thereinto through the hollow shaft 8 and the evaporation of said overflow to effect closure and opening of the automatic control valve 12-13. Furthermore the quantity of overflow into the receptacle 19—necessary to effect automatic time operation of the device—is capable of variation by adjustment of the parts 18 and 24 involved in my novel 30 valve.

While I have shown a particular construction of my automatic control valve it is to be understood the details as to form and arrangement are capable of modification within the 35 scope of the claims.

Having thus described my invention, I claim:

1. In a circulatory refrigerating system an automatic control comprising an enclosure 40 with a valved entrance for liquid refrigerant, said enclosure embodying an open-top compartment excluding refrigerant, and a flow regulator for the control of the liquid refrigerant including a pivotal duct with a counterbalanced receptacle in the open-top compartment, said receptacle swinging in one direction by added weight of refrigerant overflowing through the pivotal duct and in the opposite direction upon evaporation of 45 such added weight and part of that held in the casing to respectively close and open the valved entrance aforesaid.

2. An automatic control as claimed in claim 1, with means preventing overbalancing 55 of the receptacle when empty.

3. An automatic control as claimed in claim 1 in which the receptacle and counter-balance are relatively adjustable to vary the amount of added liquid weight necessary to 60 swing said receptacle to valve closing position.

4. An automatic control as claimed in claim 1 in which the receptacle is provided with a relatively heavy closed-in end normally overbalanced by an adjustable coun-

terweight member actuatable to close and open the inflow entrance.

5. In combination, a chamber having an entrance through which volatile liquid may flow into the chamber, a valve arranged to control the flow of liquid into the chamber, and an open pivoted receptacle within the chamber arranged to receive overflow of liquid from the chamber through its pivot and actuated by the weight of the overflow 70 to close the valve.

6. In combination, a chamber having an entrance through which volatile liquid may flow into the chamber, a valve arranged to control the flow of liquid into the chamber, and an open pivoted receptacle within the chamber arranged to receive overflow of liquid from the chamber through its pivot and rocked in one direction by the weight of the overflow to close the valve and arranged to rock in the opposite direction upon evaporation of the overflow to open the valve.

In testimony whereof, I have hereunto signed my name this 5th day of August, 1926.

FRANK A. BROWNE.
